UNITED STATES PATENT OFFICE

CHARLES W. EUNSON, OF EMERALD GROVE, WISCONSIN.

VEHICLE-POLE TIP.

SPECIFICATION forming part of Letters Patent No. 391,407, dated October 23, 1888.

Application filed May 8, 1888, Serial No. 273,212. (No model.)

To all whom it may concern:

Be it known that I, CHARLES W. EUNSON, a citizen of the United States, residing at Emerald Grove, in the county of Rock and State 5 of Wisconsin, have invented certain new and useful Improvements in Safety Attachments for Vehicle-Poles; and I do hereby declare the following to be a full, clear, and exact description of the invention, such as will enable others skilled in the art to which it appertains to 10 make and use the same.

This invention relates to certain new and useful improvements in safety appliances or attachments for vehicle-poles; and it has for 15 its object to improve generally upon the construction of appliances intended for use in preventing possible displacement, accidentally, of the neck-yoke ring from the pole of the vehicle.

20 A further object of the invention consists in providing a simple and efficient device of this kind, which may be readily and easily secured to any of the various forms of vehicle-poles now in use.

25 To these ends, and to such others as the invention may relate, the same consists in the peculiar combinations and in the novel construction, arrangement, and adaptation of parts, all as more fully hereinafter described, 30 shown in the drawings, and then sought to be particularly and definitely defined in the appended claim.

The invention is clearly illustrated in the accompanying drawings, which, with the letters of reference marked thereon, form a part 35 of this specification.

Like letters refer to like parts throughout the several views.

In the drawings, Figure 1 is a longitudinal 40 sectional view in which my invention is shown as attached to a vehicle-pole. Fig. 2 is a side elevation of the same. Fig. 3 is a perspective view of the device as it appears when detached from the pole. Fig. 4 is a detail view of the 45 spring-actuated latch.

Reference now being had to the details of the drawings by letter, A represents a vehicle-pole provided upon its under side, at a point 50 near its end, with a shoulder or pin, B, which serves to prevent the neck-yoke ring from slipping too far back upon the pole, and C repre-

sents the ring, which is secured to the center of the neck-yoke, all of which parts are of ordinary and well-known construction.

D is a casting of suitable form to adapt it to 55 be fitted to the lower face of the pole, and having its sides extended upward, so as to embrace the sides of the pole. This casting may be secured to the pole in any suitable manner, but preferably by screws or bolts passed through 60 the sides of the casting and extended into or through the pole. The lower portion of the casting D is provided with a downwardly-extended portion, E.

F is a lug or latch pivoted at a point near 65 its upper end within a vertical recess, a, formed within the extension E of the casting, the rear portion of which recess is cut away, as shown, so as to permit the latch to turn freely upon its pivot G, which is passed horizontally through 70 the extension E.

Within the upper portion of the latch or lug F is formed a recess or chamber, H, for the reception of a coiled spring, I, which spring is coiled around the pivot G, having one of 75 its ends secured to the pivot and its opposite end attached in any suitable way to the casting at the rear of the latch.

In practice the eye or ring upon the neck-yoke is passed over the end of the pole in the 80 usual manner, and as in passing along the pole it contacts with the pivoted latch F, the latch is thrown backward, and as soon as the ring has passed the end of the latch the spring I serves to at once return the latch to its normal 85 position, where it serves to prevent the ring from slipping forward or from being accidentally displaced. When it is desired to remove the neck-yoke, the latch is pressed back, and the ring is then readily removed from the pole. 90

Various expedients have heretofore been devised for locking the neck-yoke ring in place upon the vehicle-pole; but in most instances it has been sought to accomplish the object by embodying in the construction of the pole certain features of mechanism adapted to accomplish the purpose; but so far as I am aware it has not heretofore been proposed to provide a simple locking device which is adapted for use in connection with any of the various vehicle-poles now in use. Such a device I have described, and it will be readily seen that my 95 100

attachment may be quickly and easily attached to any vehicle pole or shaft without necessitating a change in either the form or construction of the pole.

5 Having thus described my invention, what I claim to be new, and desire to secure by Letters Patent, is—

The combination, with the casting D, of a latch pivoted within a vertical recess formed 10 in the lower portion of the casting, and a spring adjusted within a chamber or recess formed

within the upper portion of the latch and adapted to actuate the same, all arranged and operating substantially as described, and for the purpose specified.

15 In testimony whereof I affix my signature in presence of two witnesses.

CHARLES W. EUNSON.
